UNITED STATES PATENT OFFICE.

LUCIUS E. WEAVER, OF EAST HAMPTON, CONNECTICUT, ASSIGNOR TO THEOPHILUS KING, OF BOSTON, MASSACHUSETTS.

SEWING-MACHINE SHUTTLE.

1,326,624.

Specification of Letters Patent. Patented Dec. 30, 1919.

Application filed November 15, 1918. Serial No. 262,703.

To all whom it may concern:

Be it known that I, LUCIUS E. WEAVER, a citizen of the United States, residing at East Hampton, in the county of Middlesex and 5 State of Connecticut, have invented new and useful Improvements in Sewing-Machine Shuttles, of which the following is a specification.

This invention relates to a sewing-machine shuttle having a bobbin chamber adapted to receive a ready-wound bobbin composed of a paper cop tube and a winding of thread thereon.

The invention has for its object first, 15 to provide a shuttle of this character with improved means for controlling the rotation of the bobbin and preventing it from rotating loosely and delivering loose thread.

The invention also has for its object to 20 fully utilize the space in the bobbin chamber for the storage of thread, so that the maximum yardage of thread may be contained in the shuttle, thus enabling the shuttle to be used for a relatively long period 25 without replenishment.

The invention is embodied in the improvements which I will now proceed to describe and claim.

Of the accompanying drawings forming a 30 part of this specification,—

Figure 1 is a plan view of a shuttle embodying the invention.

Fig. 2 is a section on line 2—2 of Fig. 1.

Fig. 3 is a sectional view, showing the 35 shuttle body open for the reception of a bobbin.

Fig. 4 is a plan view of the bobbin-engaging disk, hereinafter referred to.

Fig. 5 is a section on line 5—5 of Fig. 4.

Fig. 6 is a plan view of a ready-wound 40 bobbin.

Fig. 7 is a section on line 7—7 of Fig. 6.

Fig. 8 is an enlargement of a portion of Fig. 4, showing the bobbin cop tube by 45 dotted lines.

The same reference characters indicate the same parts in all of the figures.

Figs. 1, 2 and 3 illustrate a well known 50 type of shuttle body used with the Singer sewing-machine, and known as the Singer I M shuttle. This particular type of shuttle is used for convenience of illustration, and it will be understood that my invention hereinafter described may be applied to shuttle 55 bodies otherwise constructed.

The shuttle body here shown comprises two sections 2 and 3, hinged together at 4, said sections forming a circular bobbin chamber 5, adapted to receive a ready-wound bobbin, composed of a winding 6 of 60 thread, and a paper cop tube 7, on which the thread is wound.

An abutment 8 overhangs the central portion of the chamber at one end thereof, and an annular flange 9 overhangs the margin 65 of the opposite end of the chamber. The abutment 8 is a central portion of a resilient cross bar or spring, which is adapted, as in the well known Singer shuttle, to hold the sections 2 and 3 either closed or open, the 70 shuttle body being adapted to be opened, as indicated by Fig. 3, to permit the insertion of a bobbin.

In carrying out my invention, I combine 75 with a shuttle body characterized as above described, a bobbin-engaging and controlling means next described, said means including a disk 12 rotatable in the chamber 5 in frictional contact with the flange 9, and a telescopic stud comprising an outer member 13 80 rigidly attached at one end to the disk 12, and formed externally to enter and engage the cop tube 7, and an inner member 14 arranged to bear on the abutment 8 and movable relatively to the outer member to vary 85 the length of the stud in such manner as to maintain an unvarying frictional contact between the disk 12 and the flange 9.

In the preferred embodiment of the invention here illustrated, the outer member 90 13 is tubular, and has an inwardly projecting shoulder 15 near one end of its bore, said shoulder forming an abutment for one end of a spring 16. The inner member 14 has a free sliding fit in the bore of the outer 95 member 13, and is enlarged at one end portion to form a shoulder 17 against which the opposite end of the spring 16 bears. The member 14 has a reduced portion 14^a surrounded by the spring 16, and headed or 100 upset at one end to form a bur or flange which limits the projection of the member 14 by the spring, as clearly shown by Figs. 2 and 5.

To adapt the shuttle for use, the operator 105 opens the shuttle body, as indicated by Fig. 3, and after removing the disk 12 and its telescopic stud, and withdrawing the tube 7 of a spent bobbin from the outer member of the stud, presses a filled bobbin in place 110

on the outer member 13 and then closes the body. The arrangement is such that when the body is closed, the member 14 projects sufficiently to coöperate with the abutment 5 8 in maintaining an unvarying yielding frictional contact between the marginal portion of the disk 12 and the flange 9. The body section 2 has the usual inwardly projecting flange 18 contacting with the cross 10 bar or abutment 8. When the disk 12 is pressed against the flange 9, the side of the bobbin adjacent to the flange 18 is held slightly separated from said flange, as shown by Fig. 2, so that the rotation of the bobbin 15 is retarded chiefly by the disk 12 and flange 9. A delicate and unvarying tension is thus maintained on the bobbin, preventing its loose rotation and the delivery of loose coils of thread. By unvarying, I mean that the 20 tension does not decrease as the diameter of the bobbin decreases.

The outer member 13 of the telescopic stud is preferably formed to positively engage the inner surface of the cop tube 7, and thus 25 prevent the cop tube from turning independently on the stud. To this end, the external surface of the outer member 13 is made non-cylindrical and preferably polygonal, so that it is provided with a plurality of 30 salient angles 20, adapted to indent the cop tube, as shown by Fig. 8.

It will be seen that the ready-wound bobbin does not require two heads applied to opposite ends of the bobbin, in accordance 35 with the usual practice. While the disk 12 constitutes the equivalent of one of the usual heads, the companion head usually applied to the opposite end of the bobbin is omitted, and is rendered unnecessary because the 40 telescopic stud supports said end out of contact with any part of the shuttle body, hence this end does not require protection by a head. The space occupied by the omitted head may therefore be utilized for the 45 storage of thread, the bobbin being correspondingly enlarged or lengthened.

I claim:

1. A shuttle comprising a body having a circular bobbin chamber, an abutment overhanging the central portion of the chamber at one end thereof, and an annular flange overhanging the margin of the opposite end of the chamber, a disk rotatable in said

chamber in frictional contact with said flange, and a telescopic stud comprising an 55 outer member rigidly attached at one end to said disk and formed externally to enter and so engage the cop-tube of a ready-wound bobbin as to cause said outer member and disk to rotate with the bobbin, and an inner 60 member arranged to bear on said abutment and movable relatively to the outer member to vary the length of the stud and maintain an unvarying frictional contact between said disk and flange. 65

2. A shuttle comprising a body having a circular bobbin chamber, an abutment overhanging the central portion of the chamber at one end thereof, and an annular flange overhanging the margin of the opposite end 70 of the chamber, a disk rotatable in said chamber in frictional contact with said flange, and a telescopic stud comprising a tubular outer member rigidly attached at one end to said disk and formed externally 75 to enter and so engage the cop-tube of a ready-wound bobbin as to cause the said outer member and disk to rotate with the bobbin, and a spring-pressed inner member 80 longitudinally movable in the outer member and normally projected yieldingly from the latter, said inner member bearing on said abutment and maintaining an unvarying yielding frictional contact between said disk and flange. 85

3. A shuttle comprising a body having a circular bobbin chamber, an abutment overhanging the central portion of the chamber at one end thereof, and an annular flange overhanging the margin of the opposite end 90 of the chamber, a disk rotatable in said chamber in frictional contact with said flange, and a telescopic stud comprising an outer member rigidly attached at one end to said disk and having a non-cylindrical external surface formed to positively engage the inner surface of the cop-tube of a ready-wound bobbin, and an inner member arranged to bear on said abutment and movable relatively to the outer member to vary 95 the length of the stud and maintain frictional contact between said disk and flange. 100

In testimony whereof I have affixed my signature.

LUCIUS E. WEAVER.
